UNITED STATES PATENT OFFICE.

JOHN HENRY STANTON, OF ST. CATHERINES, ONTARIO, CANADA.

AUTOMATIC CUT-OFF.

No. 892,193.

Specification of Letters Patent.

Patented June 30, 1908.

Application filed September 3, 1907. Serial No. 391,069.

To all whom it may concern:

Be it known that I, JOHN HENRY STANTON, of the city of St. Catherines, in the county of Lincoln and Province of Ontario, Canada, have invented certain new and useful Improvements in Automatic Cut-Offs; and I hereby declare that the following is a full, clear, and exact description of the same.

This invention relates to a device which 10 will automatically operate to cut off the flow of gas from the gas mains to the burners when the gas pressure falls below the pressure at which the cut off is set to operate.

The invention also relates to the construction 15 and arrangement of the parts whereby the valve can automatically adapt itself to the valve seat and form a tight contact therewith as it moves into position to cut off the gas supply through the gas outlet.

20 While the cut off can be employed to control the flow of any fluid, it is particularly designed to control the flow of gas and cut off the supply when the pressure falls below any selected amount. In the case of natural gas 25 which has a fluctuating pressure and particularly when the main cock is set to permit of only a small volume of gas passing through the gas mains, it frequently happens that the supply to the burner falls so low that the 30 draft of the air currents extinguishes the flame, resulting in the subsequent discharge of unconsumed gas from the burners. Many fatal and serious accidents have resulted from this cause, and in addition to the element of danger, the consumer sustains a loss 35 by a waste of gas from which he receives no direct or indirect benefit.

The object of the present invention is therefore to devise a simply constructed and 40 easily operated cut off which can be set to positively operate and cut off the flow of gas from the gas main to the burners when the pressure falls below the preselected amount.

45 For an understanding of the invention reference is to be had to the following description and to the accompanying drawings, in which:

Figure 1, is a vertical section of the cut off showing the position of the parts when the 50 valve is open. Fig. 2, is a similar view to Fig. 1 showing the position of the parts when the valve is closed. Fig. 3, is a horizontal section with the parts in the position shown in Fig. 1, and Fig. 4, is a similar view to Fig. 55 3, with the parts in the position shown in Fig. 2.

Like characters of reference refer to like parts throughout the specification and drawings.

In carrying out the object of this invention, I employ a valve body *a* of any suitable shape and dimensions and constructed of any suitable material and provide the valve body with an inlet port *b* and an outlet port *c*, which may be alined or angularly disposed 60 as necessity requires. The face of the outlet port *c* is finished to form a valve seat *d* for the slide valve *e*, which is arranged to automatically adapt itself to the valve seat *d* and form a tight contact therewith, to prevent 65 the escape of gas from the valve body, when positioned to close the outlet port. One means of permitting the slide valve to adapt itself to the valve seat is to loosely mount it on the valve stem *f* so that 70 it has a limited rocking and lateral movement thereon, but is prevented from moving longitudinally thereon by a key pin *g* which passes through the slide valve and enters a groove *f'* in the valve stem *f*. The valve 75 stem *f* extends through one side of the valve body *a* and through a stuffing box *h* fitted to the said side. Extending from the back of the slide valve *e* is a wedge member *i*, having an inclined face oblique to the longitudinal 80 axis of the valve stem *f* and secured within the valve body *a*, is a wedge member *j* which engages with the wedge member *i*, as the slide valve moves into position to close the 85 outlet port, and directs the slide valve against its valve seat. To facilitate the closing movement of the slide valve the valve seat *d* diverges at a small angle, preferably of about five degrees from a plane parallel with the valve stem to eliminate the frictional contact of the slide valve and valve seat during 90 the initial part of the closing movement of the slide valve. The divergence of the face of the valve seat permits the use of a light actuating spring *k*, which as shown in the 95 drawings, is of a substantially U - shape, coiled at its bend, with the free ends of its arms engaging the slide valve and the inner surface of the adjacent side of the valve body. The valve body extends slightly above the 100 top of the slide valve and fitted on the valve body is the cover *l*. Extending through the cover is a plunger *m* the lower end of which is seated on a diaphragm *n*. The diaphragm *n* is acted on by the pressure within 105 the valve body and raises the plunger *m* when the pressure in the valve body is 110

greater than the pressure at which the apparatus is set. Surrounding the plunger m on the outer side of the cover l is a stuffing box o . The plunger m extends above the top of 5 the stuffing box o , and is provided with a transverse pin p , which engages the forked end q of the operating lever r . The lever r , is fulcrumed intermediate its ends to an arm s projecting from the cover l , and is arranged 10 vertically above the valve stem f . The end of the lever r remote from the plunger m engages in a slot t in the latch u , which is employed to lock the valve stem to hold the slide valve in its open position. The latch u 15 is formed with an elliptical slot v , through which passes the outer end of the valve stem, and within the slot v are two small pointed projections w which ride on the valve stem as it moves through the slot v . The projections 20 w reduce the area of the contacting surfaces of the latch and valve stem and thus minimize the friction resulting therefrom. The valve stem f is formed with a groove x which 25 operates as a locking member to receive the latch u when the valve is in its open position and the engaging edge of the groove x is provided with a U-shape projection y which engages with the latch u to reduce the frictional 30 contact of these parts when in their holding position. Projecting from the adjacent side face of the valve body a is a bracket z having a slideway a' to guide the movement of the latch as it drops into position in the groove x , and as it is raised therefrom. An arm b' 35 extends from the valve body a on the opposite side to the arm s and projecting from the arm b' is a lug c' to which is secured an L-shaped pressure spring d' . The longitudinal arm of the L-shaped pressure spring 40 d' engages in a slot in the plunger m and the short arm of the pressure spring d' is contained between the forks of a screw threaded collar e' . Adjustable within the screw threaded collar e' , is a tension screw f' which 45 engages the short arm of the L-shaped pressure spring d' to vary the pressure of the spring on the plunger to correspond with the minimum pressure within the valve body at which it is desired to operate the cut off, the 50 action of the pressure spring moving the plunger and bringing the pin p into engagement with the forked end of the lever v . The operation of the device is as follows:— 55 The pressure of the spring d' is set by the adjustment of the tension screw f' to correspond with the pressure at which the cut off is intended to operate. The pressure of the gas in the valve body a acting on the diaphragm n raises it and the plunger m to relieve the forked end q of the lever r from the pressure of the pin p . The valve stem f is 60 manually in-pressed to displace the slide valve c from its valve seat, and when the valve stem is so positioned, the latch u 65 moves by gravity into the groove x to lock

the valve stem in its in-pressed position and thus hold the slide valve off the valve seat. While the pressure in the valve body remains at or above the preselected amount the slide valve remains positioned to open the outlet 70 port. When the pressure falls below the preselected amount, the pressure of the spring d' operates to force the plunger m and the transverse pin p towards the stuffing box o . As the pin p moves in the direction of the stuffing box o it engages the forked end q of the lever r and oscillates the lever to trip the latch u from the groove x . When the latch u is tripped from the groove x the spring k 75 moves the slide valve e on the valve seat d to close the outlet port. As the slide valve e moves on the valve seat d the engagement of the wedge members i and j directs the slide valve into contact with the valve seat so that the escape of gas from the valve body 80 through the outlet port will be effectually prevented.

By constructing and arranging the parts as above described, the action of the parts is practically co-incident with the fall of the 90 pressure in the valve body, and the continued flow of the fluid after the pressure has fallen is automatically cut off. The specific construction of the valve and valve seat and the latch and groove minimizes the friction of the 95 movement of the parts so that there is no risk of the interruption of the action of the device resulting therefrom.

Having thus fully described my invention, what I claim as new and desire to secure by 100 Letters Patent is:—

1. An automatic cut off comprising a valve body having inlet and outlet ports, a slide valve controlling the passage from the inlet port through the valve body to the outlet 105 port and movable across the face of the latter, a valve stem for the slide valve, a locking member carried by the valve stem on the outer side of the valve body, a diaphragm within the valve body actuated by the pressure in the latter, a plunger supported on the diaphragm, a lever actuated by the plunger, and a locking member on the outer side of the valve body engaging with the first mentioned locking member tripped by the actuation 110 of the lever.

2. An automatic cut off comprising a valve body having inlet and outlet ports, a slide valve stem extending through the valve body, a valve rockable on the valve stem and controlling the passage from the inlet port through the valve body to the outlet port, means to direct the valve against its valve seat, an actuating spring for the valve, a locking member for the valve stem, a latch 120 engaging with the locking member, a plunger, a diaphragm, within the valve body, for the plunger, and a lever engaging with the latch 125 and actuated by the plunger to trip the latter out of engagement with the locking member. 130

locking member, a spring for the plunger, and a slideway secured to the valve body to guide the movement of the latch.

10. An automatic cut off comprising a 5 valve body having inlet and outlet ports, a slide valve controlling the passage from the inlet port through the valve body to the outlet port, movable across the face of the latter, an actuating spring to move the slide valve 10 to close the outlet port, the slide valve being arranged to be manually opened, a diaphragm within the valve body actuated by the pres-

sure therein, a plunger supported by the dia- phragm, a locking member for the slide valve, and a locking member actuated by the plun- ger, co-acting with the first mentioned lock- ing member to hold the slide valve in its open position.
